Specification for Design.

Patented Nov. 22, 1921.

Application filed August 27, 1921. Serial No. 496,181. Term of patent 14 years.

To all whom it may concern:

Be it known that I, ROBERT IREDELL, a citizen of the United States, residing at Akron, in the county of Summit and State of Ohio, have invented a new, original, and ornamental Design for Shoe-Heels, of which the following is a specification, reference being made to the accompanying drawings, forming a part thereof.

In the drawings, Figure 1 is a plan view of the shoe heel, preferably made of rubber or similar resilient composition, and Fig. 2 is a section on the line 2—2 of Fig. 1.

I claim:

The ornamental design for a shoe heel as shown.

ROBERT IREDELL.
